UNITED STATES PATENT OFFICE.

PETER HINKEL, OF ST. LOUIS, MISSOURI.

ELEVATOR.

No. 874,339.

Specification of Letters Patent.

Patented Dec. 17, 1907.

Application filed February 19, 1907. Serial No. 358,305.

To all whom it may concern:

Be it known that I, PETER HINKEL, a citizen of the United States, and resident of St. Louis, Missouri, have invented certain new 5 and useful Improvements in Elevators, of which the following is a specification.

My invention relates to improvements in elevators, and has for its object to provide a safety device whereby the elevator car will 10 be locked in place within its shaft in the event of a breakage of the rope or cable whereby it is normally carried.

In the drawings—Figure 1 is a front plan view of a device embodying my invention, 15 showing the car in place within the vertical guides. Fig. 2 is a top plan view of the same, showing the car in place within the vertical guides located in the shaft. Fig. 3 is an end plan view of the carrying members in 20 their normal relation to each other; their abnormal relations which arise from the breakage of the rope or cable being indicated in dotted lines. Fig. 4 is a transverse vertical view in section of the carrying members, 25 taken along the line 4—4 of Fig. 1, the upper and lower transverse members being shown in their abnormal condition, arising from the breakage of the rope or cable. Fig. 5 is an enlarged perspective view of those portions 30 of the locking device embodied in my invention which engage with the guides.

As shown in the drawings, the device of my invention is interposed between the main body of the car and the ropes or cables 6 by 35 which the car is carried.

As illustrated in Fig. 1, the car 7 is provided at its top with a transverse lower carrying member 8, which member serves as a base for the frame consisting of the parallel 40 uprights 9—9 and 10—10. The lever bars 11—11 are pivotally mounted between the uprights 9—9 and 10—10 at the points indicated by the numeral 12. At their inner ends, the levers 11—11 are pivotally connected at the points indicated by the numeral 45 13 to the links 14—14; the links 14—14 are carried at the extremities of the bar 15, to which the ropes or cables 6 are attached.

The upper transverse member 16 is slidably 50 mounted between the uprights 9—9 and 10—10, and the spring 17 is mounted within the uprights 9—9 and 10—10, and is interposed between the lower transverse member 8 and the upper transverse member 16. The 55 extremities of the lower transverse member 8 are provided with cross-bars 18—18, the

cross-bars 18—18 and the end faces of the member 8 being provided with the vertical slots 19—19, which engage with the vertical guides 20 with which the elevator shaft is 60 provided. The upper transverse member 16 is provided at its extremities with the castings 21—21 which are apertured as indicated by the numeral 22 to accommodate the grips 23. The grips 23 are pivotally mounted 65 within the apertures 22 by means of the pivots 24, and at their outer extremities, said grips 23 are pivotally connected at the points indicated by the numeral 25 with the arms 26, which, in turn, are hinged at the points 70 indicated by the numeral 27 in the cross-bars 18—18, which are recessed to receive the arms 26, as indicated by the numeral 28. It will be observed that by reason of this mode of connection between the various parts, that 75 when the car is in normal operation and is being carried by the ropes or cables 6, the weight of the car causes the various parts which have been described to be in the relative positions shown in Fig. 1. When in 80 these relative positions, the slots 29 in the castings 21 are open, as indicated in Fig. 3, so that the car will slide freely upon the guides 20. In the event of the breakage of the cables 6, the bar 15 will be relieved of the 85 weight of the car and the springs 17 will force the upper transverse member 16 upward, as the levers 11 will no longer exert their downward thrust upon said member 16. Thereupon, the members 8 and 16 will be 90 forced into the relative position indicated in dotted lines in Fig. 3, and shown in Fig. 4, and the rounded inner extremities of the grips 23 will be brought together by the 95 downward pull exerted through the arms 26 by the weight of the car, so that they will contact with the side faces of the guide 20 in the manner shown in Figs. 4 and 5; the extent to which the rounded ends of the grips 23 will protrude into the slot 29 is exaggerated 100 in Fig. 4 for the purpose of indicating more clearly the mode of operation of my device.

Having fully described my invention, what I claim as new and desire to have secured to me by the grant of Letters Patent, is:

1. An improvement in elevators comprising a shaft—a car; guides located in the shaft; a plurality of uprights secured to the top of the car; a movable transverse member supported between the uprights; a spring located between the transverse member and the top of the car; levers pivotally mounted in the 110

top of the uprights the one end contacting with the upper surface of the transverse member; a bar connected to the opposite ends of the levers and to which is attached the cable; a slotted casting mounted on each end of the transverse member and a plurality of arms and grips carried in the casting, substantially as specified.

2. A device of the class described comprising an elevator shaft; guides located in the elevator shaft; a car slidably mounted upon the guides; a transverse member movably located upon the top of the car; a spring located between the transverse member and the top of the car; levers located above the transverse member, the outer ends held in de-

pressed position by the weight of the car; a plurality of grips and arms pivotally connected together and carried by the ends of the transverse member and so arranged as to cause the grips to contact with the sides of the guides in the event the car should become detached from the cable, substantially as specified.

In testimony whereof, I have signed my name to this specification, in presence of two subscribing witnesses.

PETER HINKEL.
